THOMAS D. WEST, OF CLEVELAND, OHIO.

MOLD FOR MAKING METAL CASTINGS.

1,056,961.

Specification of Letters Patent. Patented Mar. 25, 1913.

Application filed February 29, 1912. Serial No. 680,688.

To all whom it may concern:

Be it known that I, THOMAS D. WEST, a citizen of the United States of America, residing at Cleveland, in the county of Cuyahoga and State of Ohio, have invented certain new and useful Improvements in Molds for Making Metal Castings; and I hereby declare the following to be a full, clear, and exact description of the invention, such as will enable others skilled in the art to which it pertains to make and use the same.

This invention relates to improvements in molds for making metal castings, and pertains more especially to a mold suitable for use in casting a chilled annular object, such, for instance, as a chilled car-wheel.

One object of this invention is to produce a chilled car-wheel which has the greatest depth and hardness of chilling where the tread and throat of the wheel are subjected to the greatest wear and has less depth of chilling or no chilling at all where the tread and flange are subjected to little or no wear, so that the production of an excessively chilled car-wheel is avoided and a stronger and longer lived wheel is produced.

Another object is to provide the mold with simple, efficient and reliable means whereby the casting formed in the mold during the operation of the mold is most accurately centered and kept centered relative to the mold during the operation of the mold, to the end of producing a perfectly round casting which is uniformly chilled circumferentially.

Another object is to have the casting-centering means comprise radially shiftable members spaced and arranged circumferentially of the molten-metal-receiving chamber of the mold and to provide means whereby said casting-centering members during the cooling and horizontal contraction of the casting are shifted inwardly during the lateral and outward expansion by heat of the chiller or chill employed in forming the surrounding wall of said chamber, and to return said casting-centering members into their outer and normal position by and during the horizontal contraction of the chill after the lateral and outward expansion of the chill.

Another object is to cool the core of the mold interiorly by causing air or heat-absorbing medium to pass through the core in

proximity to the exterior of the core but without contact with the metal arranged next to and surrounding the core so as to cool said metal without chilling it during the chilling or cooling of the casting at the throat and tread of the wheel, and thereby prevent or greatly reduce contraction-strains internally of the casting and produce a car-wheel which is stronger and better able to withstand the shocks and abuse to which a car-wheel is subjected in general use.

Another object is to provide said core with a head instrumental in forming the bottom of a pouring-basin and to have the core provided interiorly with a metal reinforcement formed by a metal bar arranged centrally and longitudinally of the body of the core and having a head arranged centrally of and more especially reinforcing the head of the core.

Another object is to provide means whereby a heat-absorbing medium, such, for instance, as air, may be caused to pass endwise through the core between the core-reinforcing metal bar and the exterior of the body of the core and at points spaced circumferentially of said bar without coming in contact with the casting.

With these objects in view, and to the end of attaining other advantages hereinafter appearing, this invention consists in certain features of construction, and combinations and arrangement of parts, hereinafter described, pointed out in the claims, and illustrated in the accompanying drawings.

In said drawings, Figure 1 is a central vertical section of my improved mold ready for pouring. Fig. 2 is an enlarged view of a portion of Fig. 1. Fig. 3 is a view corresponding with Fig. 2, except that Fig. 3 illustrates the lateral and outward expansion of the chill by heat during the horizontal contraction of the casting. Fig. 4 is a horizontal section on line 4—4, Fig. 2, looking upwardly. Fig. 5 is a section on line 5—5, Fig. 3, looking downwardly. Fig. 6 is a horizontal section on line 6—6, Fig. 2, looking downwardly. Fig. 7 is a horizontal section on line 7—7, Fig. 2, looking upwardly. Fig. 8 is a horizontal section on line 8—8, Fig. 1, looking downwardly. Fig. 9 is a horizontal section on line 9—9, Fig. 1, looking upwardly. Fig. 10 is a horizontal

section on line 10—10, Fig. 1, looking downwardly. Fig. 11 is a vertical section on line 11—11, Fig. 1, looking inwardly. Figs. from 2 to 11 inclusive are drawn on a larger scale than Fig. 1.

The mold illustrated consists in the main of an upper mold-part or cope, a lower mold-part or drag and a central mold-part which is shown formed in the main by a sectional chiller or chill.

Referring to Fig. 1 of the drawings, A indicates a vertically arranged annular metal casing which forms a portion of the lower mold-part or drag and rests on a horizontally arranged metal plate α forming the bottom of the drag and provided with a vertically downwardly projecting annular flange 13 serving to elevate said bottom above the floor or support upon which the mold is to be mounted. The drag is rammed with sand or substantially non-chilling material, and the top or upper portion of the body of packed sand 14 of the drag has the contour required to form the bottom of the casting. B indicates a vertically arranged suitably supported annular metal casing which forms a portion of the upper mold-part or cope. The cope is rammed with sand, and the body of packed sand 15 of the cope has its bottom or lower portion contoured as required to form the top of the casting. The cope and the drag are spaced vertically to effect the formation between them of the molten-metal-receiving chamber of the mold, which chamber is enlarged diametrically and annularly at its lower end, as at c (see Figs. 1, 2, 3, and 7).

The central mold-part (see Figs. 1, 2 and 3) is instrumental in forming the surrounding wall of the chamber C and comprises a vertically arranged annular circular chiller or chill having a vertically arranged annular metal body D forming the lower portion of the chill, and metal sections E which form the upper inner annular portion of the chill and are supported from said body. The body D of the chill is preferably of cast iron, whereas the chill-sections E may be of steel. Preferably the body D is provided internally of its upper portion with an annular recess d which is concentric relative to the chamber C. Said body D has an internal surface 18 participating in the formation of the surrounding wall of the chamber C and extending from the recess d downwardly to the diametrically enlarged lower end c of said chamber. The chill-sections E are seated or rest on the bottom of the recess d and extend circumferentially of the chamber C and are instrumental in forming the upper portion of the surrounding wall of said chamber. The chill-sections E are arranged radially relative to the chamber C and have their internal surfaces or inner faces flush at their lower ends with the in-

ternal surface 18 of the body D of the chill. Adjacent chill-sections E abut against each other at their adjacent side edges.

By the construction hereinbefore described and illustrated in Figs. 1, 2 and 3 of the drawings, it will be observed that the chilling body D of the chill or central mold-part participates in the formation of the surrounding wall of the chamber C and has its internal surface 18 extending from the diametrically enlarged lower end c of said chamber upwardly about half the distance between said enlarged end of the chamber and the upper end of the chill, and that said chill also has an upper inner annular chilling portion which is formed independently of the aforesaid body of the chill and composed of sections E which are arranged substantially radially of the chill. Said construction of the chill constitutes an important portion of my present invention.

Figs. 3 and 5 show a wheel-forming casting H in the mold, and, referring to Fig. 3 of the drawings, h indicates the annular flange formed on and externally of the said casting at one end of the casting, which flange is shown formed at the lower end of the casting and has a rounded peripheral surface, and the throat 16 of the wheel is formed at the junction of the inner side of said flange with the tread 17 of the wheel. The flange of a car-wheel to be cast in the mold illustrated is obviously therefore formed next above the outer portion of the drag. The lower section or portion of the central mold-part (see Figs. 1, 2, 3, and 7) not only comprises the body D of the chill but an annular body s of sand or substantially non-chilling material. Said sand-body s is arranged to form the outer portion of the top wall and upper portion of the surrounding wall of the diametrical enlargement c of the chamber C. The outer portion of the body of packed sand 14 of the drag is contoured and arranged as required to form the bottom wall and lower portion of the surrounding wall of said enlargement of said chamber. The surrounding wall of the chamber C is formed in the main by the inner faces of the chill-sections E and by the internal circular surface 18 of the body D of the chill, and the tread of the car-wheel to be cast is formed at said surface of said body and at said faces of said chill-sections E. The inner lower portion of the body D of the chill is contoured as required to form the inner portion of the top wall of the diametrical enlargement c of the chamber C and to render said portion of said body instrumental in effecting the formation of the throat 16 of the wheel. The sand-body s preferably occupies a recess 20 formed in the lower portion of the body D of the chill and is applied to the chill in any approved manner, which recess is sub- 130

stantially concentric relative to the chill. The annular body *s* of packed sand or substantially non-chilling material adjoins the sand-body 14 of the drag. By having the 5 diametrical enlargement *c* of the molten-metal-receiving chamber C formed as hereinbefore described the flange of the car-wheel is only chilled in proximity to the throat of the wheel and undue brittleness in said 10 flange is avoided without interfering with an adequate chilling of the wheel at its throat.

The body D of the chill is mounted on the drag-casing A, and preferably, said drag-casing is provided at its top and near 15 its circumferential surface with a laterally and outwardly facing annular shoulder 22 which is overlapped by lugs 23 formed on the lower end of the body D of the chill and spaced circumferentially of said shoulder so as to prevent displacement of the said 20 body of the chill horizontally independently of the drag. The shoulder 22 and the lugs 23 are instrumental in centering the body D of the chill relative to the drag during 25 the assemblage of the component parts of the mold and are obviously relatively arranged to accommodate lateral and outward expansion by heat of said body of the chill independently of the drag. The body of 30 the chill rests at its lugs 23 on the drag-casing A. An annular space 24 is formed at the inner sides of the upper portions of the lugs 23 and between the body D of the chill and the drag-casing A and arranged substantially 35 concentrically relative to the chill and in communication between the lugs 23 with the external atmosphere. The space 24 is arranged between the recess 20 and the lugs 23, and the body of the chill is provided 40 between said recess and said space with vent-holes 21 shown extending from the top of said recess laterally and outwardly and downwardly to said space into which said vent-holes discharge. Said vent-holes are 45 spaced circumferentially of the recess 20 and permit the escape, to the space 24 and consequently to the external atmosphere from the body *s* of substantially non-chilling material, of detrimental gases created 50 within said body of substantially non-chilling material by the contact of said body with molten metal during the operation of the mold.

The body D of the chill (see Figs. 1, 2, 55 3, 4, 5, and 6) is provided at the outer side of the recess *d* with upwardly projecting lugs 27 which are spaced circumferentially of said recess and consequently circumferentially of the chamber C, and the cope-casing B is provided with downwardly projecting lugs 28 which rest on the outer portions of the lugs 27 and are spaced circumferentially of the body D of the chill. Obviously therefore the cope is mounted on the 60 body D of the chill. Each lug 28 is pro-

vided at its lower end with a laterally and outwardly projecting shoulder 30 which is overlapped by a laterally and inwardly facing shoulder 31 formed on the adjacent lug 27. The lugs 27 and 28 and their shoulders 70 31 and 30 facilitate the centering of the cope relative to the body D of the chill during the assembling of the component parts of the mold, and said shoulders 30 and 31 are relatively arranged to accommodate the 75 lateral and outward expansion of the body D of the chill by heat independently of the cope and the drag.

The chill has the inner upper portion or sections E thereof overlapped and largely covered, as at 32, (see Fig. 2) by the sand-body 15 of the cope around the chamber C, and said chamber (see Fig. 1) has a central upward enlargement 33 which is arranged in line vertically with a cavity 34 forming the lower central portion of said chamber and formed in and centrally of the sand-body 14 of the drag. The sand-body 15 of the cope is provided in its under side and next the inner faces of the chill-sections E with an annular recess 35 which is arranged concentrically relative to the chill and forms an upper annular enlargement of the chamber C, and the outer side wall of said enlargement of said chamber is formed by the portion 32 of said sand-body. The cope and the drag of the mold illustrated are shown rammed to fit them for casting a car-wheel which has a hub provided with a central bore extending therethrough, and consequently an interiorly metal-reinforced baked sand-core having a body F shown composed of sand is arranged vertically and centrally of the chamber C and extends upwardly through said chamber from the bottom of the cavity 34. The sand-body F of the core is provided at its upper end with a head *f* which is integral with said body and forms the top wall of the upward enlargement 33 of the chamber C and the bottom of a suitably formed pouring-basin 36, and said head is provided (see Figs. 1, 8 and 9) with gates 37 which establish communication between said basin and said chamber and consequently form inlets for the passage of molten metal to said chamber. The pouring-basin 36 is surrounded by a metal casing 38 which is connected with the cope-casing B by bars 39 extending substantially horizontally through the sand-body 15 of the cope.

The interior metal reinforcement of the core consists of a metal bar G which is arranged vertically centrally of the sand-body F of the core and extends from within the 125 lower end of said body upwardly into the head *f* of said body and is provided at its upper end with a head *g*. The core is provided between its exterior and the bar G with passageways 40 which (see Figs. 1 and 130

10) are parallel with and spaced circumferentially of said bar. The passageways 40 are formed directly in the sand-body F of the core and extend from within the lower 5 end of said body upwardly to the head g of the bar G and are arranged in proximity to but spaced from the exterior of said body. The sand-body 14 of the drag is provided next below the core with a chamber 41 which is in communication with the passageways 15 40; and said sand-body is provided with a hole 42 which (see Fig. 1) extends from a point centrally of the bottom of said chamber downwardly to the plate a and communicates with a passageway 43 formed in and 20 extending transversely of said plate, and the last-mentioned passageway is arranged to conduct air or heat-absorbing medium under pressure from a supply-pipe K which is provided with a normally closed valve k. The head g of the bar G is provided with laterally and outwardly projecting tubular members 45 which are spaced circumferentially of said head. Each passageway 40 (see Fig. 25 1) communicates with a hole 44 formed in the head g of the bar G. The holes 44 (see Figs. 1 and 9) are placed in communication by the tubular members 45 with an annular chamber 46 formed around the head f between the upper and lower ends of said head, which chamber is placed in communication, 30 by passageways 47 which extend from said chamber through the surrounding wall of the pouring-basin and through the cope to the top of the cope, with the external atmosphere. Upon opening the valve k air or heat-absorbing medium supplied by the pipe K is conducted to and through the passageways 40 in the core and passes from said 35 passageways to and through the tubular members 45 of the head g into the chamber 46 and thence through the passageways 47 to the external atmosphere.

I would here remark that a not unimportant feature of my present invention consists in the hereinbefore described construction of the core, and important to said construction is the formation of the passageways 40 directly in the sand-body of the core between 45 the centrally located metal reinforcement of the core and the exterior of the core and externally of and out of communication with but in proximity to the chamber C, so that said passageways are especially well adapted 50 for conducting off heat with facility from the core-surrounding body of metal during 55 the operation of the mold.

Preferably recess d has a substantially horizontally arranged bottom which (see 60 Figs. 1, 2 and 3) is provided centrally with an annular depression 49 which extends circumferentially of and is spaced from and concentric relative to the chamber C, and the chill-sections E rest on said bottom at 65 each side of said depression. Adjacent chill-

sections E (see Fig. 6) are in contact with each other at their adjacent sides. The chill-sections E extend a suitable distance above the recess d in the body D of the chill, and each chill-section E is provided at its outer side and lower end with a laterally and outwardly projecting flange 50 provided centrally (see Figs. 2, 3, and 6) with a recess 51 which extends from top to bottom of the flange. Each chill-section E tapers in cross-section toward its upper end and has its outer side sloping from the top of the flange 50 of said section upwardly and inwardly and exposed to the external atmosphere. Obviously therefore the chill-sections E are reduced in thickness toward their upper extremities, and it will be observed therefore that the chill has its upper inner annular portion which is composed of said sections E so contoured in cross-section, and said portion of the chill has such dimensions relative to the body D of the chill, that said upper inner portion of the chill has a considerably smaller heat-absorbing capacity than said body and that the mean depth of chilling of the tread-forming portion of a wheel being cast in the mold is desirably less between the central portion of the tread and the non-flanged end of the wheel than between said portion of the tread and the throat of the wheel. Hence a car-wheel cast in my improved mold has the greatest depth and hardness of chilling where the tread and throat of the wheel are subjected to the greatest wear and has less depth of chilling or is not chilled at all where the tread and flange are subjected to little or no wear, so that the production of an excessively chilled car-wheel is avoided and a stronger and longer lived wheel is produced. The approximate depth of chilling of the casting produced during the operation of my improved mold is indicated by the dotted line x in Fig. 3.

I would here remark that the recesses 51 in the flanges 50 of the chill-sections E communicate with the depression 49 in the bottom of the recess d and that said depression 49 and said recesses 51 not only effect a reduction to a minimum of the machining required to properly fit said sections to the body D of the chill but facilitate the escape into said depression of any grains of sand which may find access to the joints formed between said sections E and said body and reduce the chilling influence of said body at said joints. It will be observed also that the formation of the depression 49 under the chill-sections E leaves only uninterrupted contact circumferentially of the chamber C between the chill-body D and said chill-sections E under the inner portions of said chill-sections, so that the heat transmitted from the chill body D to the chill-sections E during the operation of the mold is reduced 130

to a minimum. The relative arrangement and contour of the chill-body D and the chill-sections E constitute an important portion of my present invention.

5 My invention also comprises means for removably securing the chill-sections E to the body D of the chill and said means (see Figs. 2, 3, 5, and 6) comprise a clamping ring L which rests on the flanges 50 of said sections E and extends horizontally across the recesses 51 in said flanges and across the sloping outer sides of said chill-sections. Said ring therefore surrounds the inner upper portion of the chill formed by said 10 chill-sections and is clamped down onto or against said flanges by clamping plates l which are spaced circumferentially of and extend over said ring and are secured, preferably removably by screws 52, to the body 15 D of the chill.

20 By the construction just described it is obvious that any chill-section or chill-sections E that may have become worn out or mutilated from any cause can be readily and 25 economically replaced.

The casting formed in the mold obviously contracts horizontally or diametrically when it cools and thereby frees the chill and obviously during the first cooling and contraction of a casting formed in the mold the chill expands laterally and outwardly by heat. Not unimportant therefore is the provision of the mold with simple, efficient and reliable means whereby the casting formed 30 in the mold during the operation of the mold is most accurately centered and kept centered relative to the mold during the operation of the mold, to the end of producing a perfectly round casting which is uniformly 35 chilled circumferentially of the casting.

40 My improved casting-centering means (see Figs. 1, 2, 3, 4, and 5), constituting a valuable portion of my present invention, comprise horizontally movable casting-centering members M which are mounted on the chill-sections E and consequently rest on the chill. Said casting-centering members M are spaced and extend circumferentially of the chamber C at the upper end of said 45 chamber and are movable horizontally and radially of the chill. Said casting-centering members are normally in their outer position and arranged to move inwardly into the chamber C. Each casting-centering member is provided at its chamber-facing side with several laterally and inwardly projecting lugs 53 which, as shown in Figs. 1, 2, 3, 4, and 5, are spaced circumferentially of the chamber C. Said lugs in the outer 50 and normal position of said casting-centering members, as shown in Figs. 1 and 2, are flush at their inner ends with the internal surfaces of the adjacent portion of the chill and participate in the formation of the 55 surrounding wall of the chamber C. The por-

tion 32 of the sand-body 15 of the cope covers and extends between the lugs 53 and participates in the formation of the upper end of the surrounding wall of the chamber C. That is, the space between adjacent lugs 53 of each casting-centering member is filled with a portion of the sand-body 15 of the cope. Preferably each lug 53 has opposite sides thereof converging downwardly, and adjacent edges of adjacent casting-centering members M are preferably beveled, as at 54, and face upwardly, as shown in Fig. 11, and the sand-body 15 of the cope extends, as at 55, between and covers said edges of said casting-centering members. By the provision of the casting-centering members with the peculiarly shaped lugs 53 hereinbefore described and the spacing of said lugs circumferentially of the chamber C and the extension of the sand-body 15 of the cope between adjacent lugs of each casting-centering member, my improved casting-centering means is rendered adequately positive, and detrimental chilling of the casting formed in the mold by the casting-centering means 60 is successfully avoided.

65 Each casting-centering member M has two laterally and outwardly projecting arms m which are spaced circumferentially of the chamber C, and a laterally bowable leaf-spring Q is arranged at the outer side of said casting-centering member and overlaps the outer end-faces of said arms and in the outer and normal position of said casting-centering member extends straight between 70 said arms, as shown in Fig. 4, which spring is attached to or operatively connected with said arms in any approved manner and said spring rests at its lower edge on a lug 27 of the body D of the chill, as shown in Figs. 1, 2, 3, and 5, which lug therefore participates in supporting said casting-centering member. Two vertically spaced abutments R for the inner side of said spring are provided, which abutments are arranged centrally between the arms m connected together by said spring and consist preferably of two vertically spaced screws which are arranged horizontally and substantially radially of the chill and screwed into an upwardly projecting member 29 of a lug 27 of the body D of the chill. Said abutments are therefore adjustable radially of the chill and have preferably such adjustment relative to the adjacent spring that they shall engage 75 the inner side of said spring in the outer and normal position of the casting-centering member operatively connected with said spring. Two abutments T for the outer side of said spring are provided, which abutments 80 are spaced longitudinally of the spring and substantially equidistantly from opposite ends respectively of the spring. The outer abutments T for said spring are arranged between the arms m connected together by 85

said spring, and the inner abutments R for said spring are arranged centrally between and equidistantly from said outer abutments. The outer abutments T for said spring preferably comprise two screws which are arranged horizontally and substantially radially of the chill, which screws are screwed into the lugs 28 of the cope-casing B, and said outer abutments are therefore supported independently of the chill.

I would here remark that the arms m of the casting-centering members M possess enough springiness to render them capable of yielding to the connected spring Q during the lateral and outward bowing of said springs, and it will be observed that the inner abutments R for said springs, during the outward movement of said abutments with the lateral and outward expansion of the chill by heat during the horizontal contraction or cooling of the casting, bow said springs outwardly between the outer abutments T for the springs, as shown in Fig. 5; that said outer abutments T resist the lateral and outward bowing of the springs from end to end and thereby cause the end-portions of the springs to move laterally and inwardly and thereby actuate the casting-centering members M inwardly into the chamber C to keep the casting accurately centered during the horizontal contraction or cooling of the casting; that the inner abutments R for the springs move laterally and inwardly during the horizontal contraction of the chill after the lateral and outward expansion of the chill by heat and thereby permit the springs to return to their normal position shown in Fig. 4, and that obviously the return of said springs to their normal position effects the return of the casting-centering members M into their outer and normal position.

It will be observed that by the construction hereinbefore described the passageway 43 employed in conducting a heat-absorbing medium is formed at one end of the mold and arranged externally of and out of communication with the molten-metal-receiving chamber C and extends to the exterior of the mold; that a passageway or passageways 47 are formed at the opposite end of the mold and externally of and out of communication with said chamber and extend to the exterior of the mold; that passageways 40 formed interiorly of the core of the mold between the central portion of said core and the exterior of the core are out of communication with the chamber C but placed in communication with the aforesaid passageways 43 and 47 and spaced circumferentially of said central portion of the core; that the valved supply pipe K constitutes means whereby a heat-absorbing medium may be caused to pass through said passageways, that said heat-absorbing medium,

upon opening the valve k of said supply pipe during the operation of the mold, is conducted to and through the core in proximity to the exterior of the core but without contact with the metal arranged next to and surrounding the core during the operation of the mold so as to cool said metal without chilling it during the chilling or cooling of the casting circumferentially and thereby prevent or greatly reduce contraction-strains internally of the casting and produce a casting better fitted to possess the requisite strength and ability to successfully withstand shocks and abuse. I would also remark that the portion 32 of the sand-body 15 of the cope is carried by and with the lugs 53 of the casting-centering members M, as shown in Figs. 3 and 5, during the inward movement of said casting-centering members.

What I claim is:—

1. In a mold for making metal castings, the combination, with movable casting-centering members spaced circumferentially of and normally arranged to move inwardly into the molten-metal-receiving chamber of the mold, of springs arranged to actuate the casting-centering members, and means whereby the springs are caused to actuate the casting-centering members inwardly during the cooling and horizontal contraction of the casting formed in said chamber.

2. In a mold having a circular molten-metal-receiving chamber, the combination, with horizontally movable casting-centering members extending and spaced circumferentially of and normally arranged to move inwardly into said chamber, of springs arranged at the outer sides of and operatively connected with the casting-centering members, and means whereby the springs are caused to actuate the casting-centering members inwardly during the cooling and horizontal contraction of the casting formed in said chamber.

3. In a mold having a circular molten-metal-receiving chamber, the combination, with horizontally movable casting-centering members extending and spaced circumferentially of and normally arranged to move inwardly into said chamber, each casting-centering member having two laterally and outwardly projecting arms which are spaced circumferentially of the chamber, of a laterally bowable spring extending between said arms, and means whereby the spring is caused to actuate the connected casting-centering member inwardly during the cooling and horizontal contraction of the casting formed in said chamber.

4. In a mold having a circular molten-metal-receiving chamber, the combination, with horizontally movable casting-centering members extending and spaced circumferentially of the chamber, of a laterally bowable spring extending between the outer ends of the casting-centering members, and means whereby the spring is caused to actuate the casting-centering members inwardly during the cooling and horizontal contraction of the casting formed in said chamber.

5 tially of and normally arranged to move inwardly into said chamber, each casting-centering member having two laterally and outwardly projecting arms which are spaced circumferentially of said chamber, of a laterally bowable spring overlapping the outer end faces of said arms, and means whereby the spring is caused to actuate the connected casting-centering member inwardly during the cooling and horizontal contraction of the casting formed in said chamber.

10 5. In a mold for making metal castings, the combination, with a vertically arranged chill participating in the formation of the molten-metal-receiving chamber of the mold, and casting-centering means normally arranged to be operated to center a casting formed in said chamber, of springs for effecting the operation of said casting-centering means to center the casting formed in said chamber, and means whereby the springs are caused to operate said casting-centering means to center the casting during the lateral and outward expansion of the 25 chill by heat.

15 6. In a mold for making a circular metal casting, the combination, with a vertically arranged chill participating in the formation of the surrounding wall of the molten-metal-receiving chamber of the mold, and movable casting-centering members spaced circumferentially of and normally arranged to move inwardly into said chamber, of springs operatively connected with the casting-centering members, and means whereby the springs are caused to actuate the casting-centering members inwardly during the lateral and outward expansion of the chill by heat.

20 7. In a mold for making metal castings, the combination, with a vertically arranged chill participating in the formation of the molten-metal-receiving chamber of the mold, and horizontally movable casting-centering members extending and spaced circumferentially of and normally arranged to move inwardly into said chamber, of laterally facing leaf-springs arranged at the outer sides of the casting-centering members, and means whereby the springs are caused to actuate the casting-centering members inwardly during the lateral and outward expansion of the chill by heat.

25 8. In a mold for making a circular metal casting, the combination, with a vertically arranged chill participating in the formation of the surrounding wall of the molten-metal-receiving chamber of the mold, and horizontally movable casting-centering members extending and spaced circumferentially of and normally arranged to move inwardly into said chamber, each casting-centering member having two laterally and outwardly projecting spaced arms, of a

30 arms, and means whereby said spring is caused to actuate the connected casting-centering member inwardly during the lateral and outward expansion of the chill by heat.

35 9. In a mold for making metal castings, the combination, with a chill participating in the formation of the molten-metal-receiving chamber of the mold, and movable casting-centering members spaced circumferentially of and normally arranged to move inwardly into said chamber, of springs instrumental in actuating the casting-centering members inwardly and outwardly relative to said chamber and having the operation thereof for effecting the inward movement of the casting-centering members controlled by the lateral and outward expansion of the chill by heat, and having the operation thereof for effecting the outward movement of the casting-centering members after said expansion of the chill controlled by the contraction of the expanded chill.

40 10. In a mold for making metal castings, the combination, with a vertically arranged chill participating in the formation of the molten-metal-receiving chamber of the mold, and movable casting-centering members spaced circumferentially of and normally arranged to move inwardly into said chamber, each casting-centering member having two laterally and outwardly projecting spaced arms, of a laterally bowable spring extending between and operatively connected with said arms; two abutments for the outer side of the spring, which abutments are arranged between said arms and spaced longitudinally of the spring and supported independently of the chill, and an abutment for the inner side of the spring, said last-mentioned abutment being carried by the chill and arranged between and spaced from the first-mentioned abutments.

45 11. In a mold for making metal castings, the combination, with a vertically arranged chill participating in the formation of the molten-metal-receiving chamber of the mold, and movable casting-centering members spaced circumferentially of and normally arranged to move inwardly into said chamber, each casting-centering member having two laterally and outwardly projecting arms spaced circumferentially of said chamber, of a laterally bowable spring extending between and operatively connected with said arms; two abutments for the outer side of the spring, which abutments are spaced longitudinally of the spring and supported independently and adjustable substantially radially of the chill, and an abutment for the inner side of the spring, said last-mentioned abutment being carried by the chill and arranged between and spaced from the first-mentioned abutments.

50 12. In a mold for making metal castings, the combination, with a vertically arranged

- chill participating in the formation of the molten - metal - receiving chamber of the mold, and movable casting-centering members spaced circumferentially of and normally arranged to move inwardly into said chamber, each casting - centering member having two laterally and outwardly projecting arms spaced circumferentially of said chamber, of a laterally bowable spring 10 extending between and operatively connected with said arms; two abutments for the outer side of the spring, which abutments are spaced longitudinally of the spring and supported independently of the 15 chill, and an abutment for the inner side of the spring, said last-mentioned abutment being carried by and adjustable substantially radially of the chill and arranged between and spaced from the first-mentioned 20 abutments.
13. In a mold for making metal castings, the combination, with a vertically arranged chill participating in the formation of the molten - metal - receiving chamber of the 25 mold, and movable casting-centering members spaced circumferentially of and normally arranged to move inwardly into said chamber, each casting - centering member having two laterally and outwardly projecting arms spaced circumferentially of 30 said chamber, of a laterally facing leaf - spring extending between and operatively connected with said arms; two abutments for the outer side of the spring, which abutments are spaced longitudinally of the 35 spring and supported independently of the chill, and two vertically spaced abutments for the inner side of the spring, said last-mentioned abutments being carried by the 40 chill and arranged between and spaced from the first-mentioned abutments.
14. In a mold for making metal castings, the combination, with a vertically arranged chill participating in the formation of the 45 molten - metal - receiving chamber of the mold, and movable casting-centering members arranged over and resting on the chill and spaced and extending circumferentially of and normally arranged to move inwardly 50 into said chamber, each casting-centering member having two laterally and outwardly projecting arms which are spaced circumferentially of said chamber, and a laterally bowable spring extending between 55 and operatively connected with said arms, of an abutment for the inner side of the spring, which abutment is carried by the chill and arranged centrally between said arms, and two abutments for the outer side 60 of the spring, said last-mentioned abutments being spaced longitudinally and substantially equidistantly from opposite ends respectively of the spring and supported independently of the chill.
- 65 15. In a mold for making metal castings,

the combination, with a vertically arranged chill participating in the formation of the molten - metal - receiving chamber of the mold, and movable casting-centering members spaced circumferentially of and normally arranged to move inwardly into said chamber, each casting - centering member having two laterally and outwardly projecting spaced arms, and a laterally facing leaf - spring extending between and operatively connected with said arms, of an abutment for the inner side of the spring, which abutment is carried by the chill and arranged centrally between said arms, and two screws forming abutments for the outer side of the spring, which screws are spaced longitudinally of the spring and substantially equidistantly from opposite ends respectively of the spring and supported independently and arranged substantially radially of the chill. 70

16. In a mold for making metal castings, the combination, with a vertically arranged chill participating in the formation of the molten - metal - receiving chamber of the 90 mold, and movable casting-centering members spaced circumferentially of and normally arranged to move inwardly into said chamber, each casting - centering member having two laterally and outwardly projecting spaced arms, and a laterally facing leaf - spring extending between and operatively connected with said arms, of a screw 95 forming an abutment for the inner side of the spring, which screw is carried by the chill and arranged substantially radially of the chill and centrally between said arms, and two abutments for the outer side of the 100 spring, said last-mentioned abutments being spaced longitudinally of the spring and substantially equidistantly from opposite ends respectively of the spring and supported independently of the chill. 105

17. In a mold for making metal castings, the combination, with a lower mold-part or 110 drag; an upper mold-part or cope arranged above and spaced from the drag to form a chamber between the drag and the cope, which chamber has an inlet for the passage of molten metal to the chamber; a vertically arranged chill participating in the formation of the surrounding wall of said chamber and being free to expand laterally and outwardly by heat independently of the cope and drag, and horizontally movable casting-centering members mounted on the chill and spaced circumferentially of and normally arranged to move inwardly into said chamber, each casting-centering member having two laterally and outwardly spaced arms, of 115 a laterally bowable spring extending between and operatively connected with said arms; an abutment for the inner side of the spring, which abutment is arranged centrally between said arms and carried by the 120

125

130

chill, and two abutments for the outer side of the spring, said last-mentioned abutments being spaced longitudinally of the spring and substantially equidistantly from opposite ends respectively of the spring and carried by the cope.

18. In a mold for making a circular casting, a lower mold-part or drag; an upper mold-part or cope arranged above and spaced from the drag to form a chamber between the drag and the cope and being rammed with a body of packed sand, said sand-body forming the top wall of the chamber; a vertically arranged chill instrumental in forming the surrounding wall of the chamber, and suitably supported movable casting-centering members spaced circumferentially of and normally arranged to move inwardly into the chamber, each casting-centering member being provided at its chamber-facing side with several laterally and inwardly projecting lugs which participate in the formation of the surrounding wall and are spaced circumferentially of the chamber, the sand-body of the cope covering and extending between the casting-centering members, and the space between adjacent lugs of said casting-centering member being filled by a portion of said sand-body.

30 19. In a mold for making a circular casting, a lower mold-part or drag; an upper mold-part or cope arranged above and spaced from the drag to form a chamber between the drag and the cope and being rammed with a body of packed sand, said sand-body forming the top wall of the chamber; a vertically arranged chill instrumental in forming the surrounding wall of the chamber, and suitably supported movable casting-centering members spaced circumferentially of and normally arranged to move inwardly into the chamber, each casting-centering member being provided at its chamber-facing side with laterally and inwardly projecting lugs which are spaced circumferentially of the chamber and participate in the formation of the surrounding wall of the chamber, the sand-body of the cope covering and extending between said lugs and between adjacent portions of adjacent casting-centering members, each lug of each casting-centering member having its sides converging downwardly.

20. In a mold for making metal castings, a drag; a cope arranged above and spaced from the drag to form a molten-metal-receiving chamber between the cope and the drag and having a pouring-basin which is arranged centrally of the cope and in communication with said chamber; a central mold-part arranged between the cope and the drag and instrumental in forming the surrounding wall of said chamber, and an interiorly metal-reinforced sand-core arranged centrally of the chamber and having

a sand-body which extends vertically from top to bottom of the chamber and is contoured at its upper end to form a head forming the bottom of the pouring-basin, said core having its interior metal-reinforcement consisting of a metal bar which is arranged centrally of the core and extends from within the lower end of the aforesaid sand-body upwardly into the head of said sand-body and terminates at its upper end in a head arranged within said head of said sand-body.

21. In a mold for making metal castings, a molten-metal-receiving chamber; a passageway for conducting a heat-absorbing medium, which passageway is formed at one end of the mold and externally of and out of communication with said chamber and extends to the exterior of the mold; a passageway formed at the opposite end of the mold and externally of and out of communication with said chamber and extending to the exterior of the mold; a core extending through said chamber and provided internally between its central portion and its exterior with passageways which are arranged externally of and out of communication with said chamber but placed in communication with the aforesaid passageways and spaced circumferentially of said central portion of the core, and means whereby a heat-absorbing medium may be caused to pass through said passageways.

22. In a mold for making metal castings, a molten-metal-receiving chamber; a drag forming the bottom of said chamber and provided externally of and out of communication with said chamber with a passageway for conducting a heat-absorbing medium, which passageway extends to the exterior of the mold; a cope forming the top wall of said chamber and provided with a passageway which is arranged externally of and out of communication with the chamber and extends to the exterior of the mold; a core extending from top to bottom of the chamber and provided internally between its central portion and its exterior with passageways which are spaced circumferentially of said central portion and extend endwise of the core, said passageways in the core being out of communication with said chamber but placed in communication with the aforesaid passageways in the cope and drag, and means whereby a heat-absorbing medium may be caused to pass through said passageways.

23. In a mold for making metal castings, the combination, with a drag; a cope arranged above and spaced from the drag to form a molten-metal-receiving chamber between the cope and the drag; a central mold-part arranged between the cope and the drag and instrumental in forming the surrounding wall of said chamber, and a

core arranged centrally of the chamber and extending vertically from top to bottom of the chamber, of means whereby a heat-absorbing medium may be caused to pass externally of and out of communication with said chamber through the mold from one end to the other end of the mold and endwise through the core between the central portion and the exterior of the core and at 10 points spaced circumferentially of said central portion of the core.

24. In a mold for making metal castings, a drag; a cope arranged above and spaced from the drag to form a molten-metal-receiving chamber between the cope and the 15 drag and having a pouring-basin which is arranged centrally of the cope and in communication with said chamber, said cope having passageways which are out of communication with said chamber and spaced circumferentially of the pouring-basin and extend to the exterior of the mold; a central mold-part arranged between the cope and the drag and instrumental in forming 20 the surrounding wall of said chamber; a core arranged centrally of the chamber and extending from top to bottom of the chamber and provided interiorly between its central portion and the exterior of the core with 25 passageways which extend endwise of the core and are out of communication with said chamber but placed in communication at the upper end of the core with the aforesaid passageways in the cope, and means whereby 30 a heat-absorbing medium may be caused to pass through said passageways.

25. In a mold for making metal castings, a drag having a horizontally arranged plate at the bottom, which plate is provided interiorly with a passageway; a cope arranged above and spaced from the drag to form a molten-metal-receiving chamber between the cope and the drag; a central mold-part arranged between the cope and the drag and 40 instrumental in forming the surrounding wall of said chamber; a core extending from top to bottom of the chamber, and means whereby a heat-absorbing medium may be caused to pass between the top of the cope 45 and the aforesaid passageway endwise through the core but externally of and out of communication with said chamber.

26. In a mold for making metal castings, a drag; a cope arranged above and spaced 55 from the drag to form a molten-metal-receiving chamber between the cope and the drag and having a pouring-basin which is arranged centrally of the cope and in communication with said chamber; a central mold-part arranged between the cope and the drag and instrumental in forming the 60 surrounding wall of said chamber; an interiorly metal-reinforced sand-core arranged centrally of the chamber and extending 65 from top to bottom of the chamber, which

core has its interior metal reinforcement consisting of a metal bar arranged centrally of the core and extending from within the lower end into the upper end of the core and provided at its upper end with laterally projecting tubular members spaced circumferentially of the bar, said core being provided between the aforesaid bar and the exterior of the core with passageways spaced circumferentially of said bar and extending longitudinally of the core and placed in communication with the aforesaid tubular members, and means whereby a heat-absorbing medium may be caused to pass through said passageways.

27. In a mold for casting chilled car-wheels, a central mold-part instrumental in forming the surrounding wall of the molten-metal-receiving chamber of the mold, which chamber is enlarged diametrically at its 70 lower end, said mold-part comprising a chill having a vertically arranged annular chilling body which has an internal surface participating in the formation of said wall and extending from the diametrically enlarged lower end of said chamber upwardly about half the distance between said enlarged end of the chamber and the upper end of the chill, said chill also having an upper inner annular chilling portion which participates in the formation of said wall and is formed independently of said body of the chill and tapers toward its upper end, said upper portion of the chill only having a part of its bottom in contact with said body.

28. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular chilling body provided internally of its upper portion with an annular recess which extends circumferentially of said chamber and has a bottom provided with an annular depression spaced from and extending circumferentially of said chamber, said body having an internal surface which participates in the formation of the aforesaid wall and extends from the aforesaid bottom downwardly to the diametrically enlarged lower end of said chamber, the chill also having an upper inner annular chilling portion which participates in the formation of said wall and is formed independently of the body of the chill and seated on said bottom between said chamber and the aforesaid depression.

29. In a mold for casting chilled car-wheels, a central mold-part instrumental in forming the surrounding wall of the molten-metal-receiving chamber of the mold, which chamber is enlarged diametrically at its 80 85 90 95 100 105 110 115 120 125 130

- lower end, said mold-part comprising a chill having a vertically arranged annular chilling body provided internally of its upper portion with an annular recess which extends circumferentially of said chamber, said body having an internal surface which participates in the formation of the aforesaid wall and extends from said recess downwardly to the diametrically enlarged 10 lower end of said chamber, the chill also having an upper inner annular chilling portion which participates in the formation of said wall and is formed independently of the body of the chill and seated on the bottom of said recess and has an unbroken contact with said bottom, circumferentially of the aforesaid chamber, only under the inner part of the bottom of said upper portion of the chill.
- 20 30. In a mold for casting chilled car-wheels, a central mold-part instrumental in forming the surrounding wall of the molten-metal receiving chamber of the mold, which chamber is enlarged diametrically at its lower end, said mold-part comprising a chill having a vertically arranged annular chilling body provided internally of its upper portion with an annular recess which extends circumferentially of said chamber and has a bottom which is provided with an annular depression arranged centrally of said bottom and extending circumferentially of said chamber, said body having an internal surface participating in the formation of the aforesaid wall and extending from said recess downwardly to the diametrically enlarged lower end of said chamber, said chill having an upper inner annular chilling portion which participates 35 in the formation of said wall and is formed independently of the body of the chill and seated on the aforesaid bottom at opposite sides of the depression in said bottom.
31. In a mold for casting car-wheels, a central mold-part instrumental in forming the surrounding wall of the molten-metal-receiving chamber of the mold, which chamber is enlarged diametrically at its lower end, said mold-part comprising a chill having a vertically arranged annular chilling-body provided internally of its upper portion with an annular recess extending circumferentially of said chamber, said body having an internal surface participating in the formation of the aforesaid wall and extending from said recess downwardly to the diametrically enlarged lower end of said chamber, the chill also having an upper inner annular chilling portion which participates 40 in the formation of said wall and is formed independently of the body of the chill and seated on the bottom of said recess, and means for preventing displacement of said upper portion of the chill upwardly from said body of the chill, said means be-

ing arranged externally and accessible at the upper end of said upper portion of the chill.

32. In a mold for casting car-wheels, a central mold-part instrumental in forming the surrounding wall of the molten-metal-receiving chamber of the mold, which chamber is enlarged diametrically at its lower end, said mold-part comprising a chill having a vertically arranged annular chilling body provided internally of its upper portion with an annular recess extending circumferentially of said chamber, said body having an internal surface participating in the formation of the aforesaid wall and extending from said recess downwardly to the diametrically enlarged lower end of said chamber, said chill having an upper inner annular chilling portion which participates in the formation of said wall and is formed independently of the body of the chill and seated on and clamped to the bottom of the aforesaid recess.

33. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular chilling body which has an internal surface participating in the formation of said wall and extending upwardly from the diametrically enlarged lower end of said chamber, said chill also having an upper inner annular chilling portion which is composed of sections which participate in the formation of said wall and are arranged substantially radially relative to said chamber, adjacent sections of said upper portion of the chill being in contact with each other at their adjacent sides.

34. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular chilling body which has an internal surface participating in the formation of said wall and extending upwardly from the diametrically enlarged lower end of said chamber, said chill also having an upper annular chilling portion which is composed of suitably supported sections which participate in the formation of said wall and are arranged substantially radially relative to said chamber and reduced in thickness toward their upper extremities.

35. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular

chilling body which has an internal surface participating in the formation of said wall and extending from the diametrically enlarged lower end of said chamber upwardly about half the distance between said enlarged end of the chamber and the upper end of the chill, said chill also having an upper inner annular chilling portion which is composed of sections which participate in the formation of said wall and are seated on the body of the chill and arranged substantially radially relative to said chamber and taper upwardly in cross-section.

36. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular chilling body which has an internal surface participating in the formation of said wall and extending upwardly from the diametrically enlarged lower end of said chamber, said chill also having an upper inner annular chilling portion which is composed of sections which are mounted on the aforesaid body and participate in the formation of the aforesaid wall and are arranged substantially radially relative to said chamber but removably secured in place on said body.

37. In a mold for casting chilled car-wheels, a central mold-part instrumental in forming the surrounding wall of the molten-metal-receiving chamber of the mold, which chamber is enlarged diametrically at its lower end, said mold-part comprising a chill having a vertically arranged annular chilling body which has an internal surface participating in the formation of said wall and extending upwardly from the diametrically enlarged lower end of said chamber, said body being provided internally of its upper portion with an annular recess, the chill also having an upper inner annular chilling portion which is composed of sections which participate in the formation of said wall and are arranged radially relative to said chamber and seated and removably secured to the bottom of the aforesaid recess.

38. In a mold for casting chilled car-wheels, a central mold-part comprising a chill having a vertically arranged annular chilling body participating in the formation of the surrounding wall of the molten-metal-receiving chamber of the mold, said chill also having an upper inner annular chilling portion which is composed of sections which are seated on said body and arranged substantially radially relative to and extend circumferentially of said chamber, which sections participate in the formation of the aforesaid wall and are provided at their lower ends with laterally and outwardly projecting flanges; a member resting

on said flanges and extending circumferentially of the upper inner annular chilling portion, and means for preventing upward displacement of said circumferentially extending member.

39. In a mold for casting chilled car-wheels, a central mold-part comprising a chill having a vertically arranged annular chilling body participating in the formation of the surrounding wall of the molten-metal-receiving chamber of the mold, said chill also having an upper inner annular chilling portion which is composed of sections which are seated on said body and arranged substantially radially relative to and extend circumferentially of said chamber, which sections participate in the formation of the aforesaid walls and are provided at their lower ends with laterally and outwardly projecting flanges, said clamping ring resting on said flanges and extending horizontally across the outer sides of said sections, and means whereby said ring is clamped downwardly against said flanges.

40. In a mold for casting chilled car-wheels, a central mold-part comprising a chill having a vertically arranged annular chilling body participating in the formation of the surrounding wall of the molten-metal-receiving chamber of the mold, said chill also having an upper inner annular chilling portion which is composed of sections which are seated on said body and participate in the formation of said wall, which sections are provided at their lower ends with laterally and outwardly projecting flanges; a clamping ring resting on said flanges and extending horizontally across the outer sides of said sections, and clamping plates spaced circumferentially of and extending over said clamping ring and secured to the body of the chill, which plates clamp said ring to said flanges.

41. In a mold for casting chilled car-wheels, a central mold-part comprising a chill having a vertically arranged annular chilling body participating in the formation of the surrounding wall of the molten-metal-receiving chamber of the mold, said body being provided internally of its upper portion with an annular recess which is concentric relative to said chamber, said chill having an upper inner annular chilling portion which is composed of sections which are seated on the bottom of said recess, which sections are arranged substantially radially relative to and extend circumferentially of said chamber and participate in the formation of the aforesaid wall, and means whereby said sections are clamped to the bottom of said recess.

42. In a mold for casting chilled car-wheels, a central mold-part comprising a chill having a vertically arranged annular chilling body participating in the formation

of the surrounding wall of the molten-metal-receiving chamber of the mold, said body being provided internally of its upper portion with an annular recess which is concentric relative to said chamber and has its bottom provided with an annular depression arranged centrally of said bottom and extending circumferentially of said chamber, said chill having an upper inner annular chilling portion composed of sections which are seated on said bottom at opposite sides of said depression, which sections participate in the formation of the aforesaid wall and are provided at their lower ends with laterally and outwardly projecting

flanges provided with recesses extending from top to bottom of the flanges and in communication with the aforesaid depression; a clamping ring resting on said flanges and extending horizontally across the outer 20 sides of said sections, and means whereby said clamping ring is clamped downwardly against said flanges.

In testimony whereof, I sign the foregoing specification, in the presence of two 25 witnesses.

THOMAS D. WEST.
